UNITED STATES PATENT OFFICE.

FRANK R. LANZILLOTTA, OF LYNCH, KENTUCKY.

CRUTCH.

Application filed February 11, 1924. Serial No. 692,077.

To all whom it may concern:

Be it known that I, FRANK R. LANZILLOTTA, a citizen of the United States of America, residing at Lynch, in the county of Harlan and State of Kentucky, have invented certain new and useful Improvements in Crutches, of which the following is a specification.

This invention relates to new and useful 10 improvements in crutches.

It is well known to those familiar with the use of crutches that the same, during use, are moved in arcuate paths or swung about fulcrum points and that the said fulcrum points are usually the arm pits of the user. This swinging or pivoting of a crutch causes the head portion to rub the arm pit and this rubbing action quickly damages the user's clothing and also chafes his body, 20 thereby, forming fleshburns or sores.

The primary object of this invention is to provide a crutch that will prevent chafing of the arm pits of the user and will also insure against the usual damaging of his 25 clothes.

Other objects and advantages of the invention will be apparent during the course of the following description.

In the accompanying drawing forming a 30 part of this specification and in which like numerals are employed to designate like parts throughout the same,

Figure 1 is a fragmentary side elevational view of the upper portion of a crutch and illustrates in dotted lines the adaptability of the shaft portion to move in respect to the auxiliary head portion.

Figure 2 is an end elevational view of Fig. 1,

Figure 3 is a vertical sectional view of the head portion of the crutch shown in Fig. 1 and taken upon line III—III of that figure,

Figure 4 is a top plan view of the head 45 portion of the crutch illustrated in Fig. 1,

Figure 5 is a partly sectional view, partly top plan view taken upon line V—V of Fig. 1, and

Figure 6 is a fragmentary perspective 50 view of the head portion and auxiliary head portion of the crutch embodying this invention.

In the drawing, wherein for the purpose of illustration is shown a preferred embodi-

ment of this invention, the numeral 5 designates the staff portion of the crutch which is of the usual or more popular form, to wit: the split staff. Permanently secured to the upper ends of this split staff 5 is the stationary, arcuately formed head portion 6 which is provided with a dove-tail-shaped, longitudinally extending groove 7 which is of arcuate outline to conform with the general shape of the head 6. It is to be understood that this dove-tail-shaped groove 7 is open at each end and is also open at its inner periphery.

Longitudinally slidably associated with the stationary head portion 6 is the movable, auxiliary head portion 8 which is formed 70 with the dove-tail-shaped, arcuate rib 9, as illustrated. It is to be understood that this dove-tail-shaped rib 9 is to be slidably retained within the dove-tail-shaped groove 7 formed in the head 6. At one end of this 75 auxiliary head portion 8, the same projects laterally, as at 10, beyond the opposite side walls of the dove-tail-shaped rib 9 for the purpose of engaging the end wall 11 of the head portion 6 to limit the sliding movement of the auxiliary head portion 8 in one direction. The opposite end of the auxiliary head portion 8 is provided with a removable block 12 which limits the movement of the said head portion 8 in the opposite 80 direction and provides means, when removed for permitting the dove-tail-shaped rib 9 to be inserted within the dove-tail-shaped groove 7.

For the purpose of permitting free relative movement between the head portion 6 and the auxiliary head portion 8, ball bearings 13, best illustrated in Figs. 1 and 3, are provided and substantially carried by the head portion 6, but projecting a sufficient 95 distance therefrom to engage the under surfaces of the auxiliary head portion 8.

In Fig. 1 the auxiliary head portion 8 is shown in full lines in one position while the head portion 6 and split staff 5 are shown 100 in full lines in one position and in dotted lines in a different position. This is intended to illustrate the broad utility of the invention which consists of means for preventing chafing of the user's armpits and 105 his clothing directly associated therewith by providing an auxiliary head portion 8 that will remain stationary in respect to the

arm pit and is permitted to move in respect to the head portion 6 and the split staff 5. In other words, the portion engaging the user's clothing and bearing against his arm-
5 pit is the auxiliary head portion 8, which remains stationary in respect thereto. The head portion 6 and staff 5 will be swung around the auxiliary head portion 8 for permitting the usual swinging or fulcruming
10 of the crutch staff.

It is to be understood that the form of this invention herewith shown and described is to be taken as a preferred example of the same, and that various changes in the shape,
15 size, and arrangement of parts may be resorted to without departing from the spirit of the invention or the scope of the subjoined claim.

Having thus described the invention, I claim:—

The combination with a crutch top having its upper surface in the form of a circular arc and provided with a dovetail groove extending the full length of the top to open at each end, an arm support having 25 an arcuate under surface provided with a dovetail tongue and conforming in shape to the grooved surface of the crutch top to fit closely thereto throughout its length, said support being longer than the crutch top, 30 and stop members fixed to the ends of said support to engage the ends of the crutch top and limit its movement.

In testimony whereof I affix my signature.

FRANK R. LANZILLOTTA.
